ABSTRACT

Elongated workpieces are axially positioned in a chamber formed with a cavity that is designed to axially guide a die that is forced through the cavity over the workpiece. In one embodiment a tubular workpiece is shaped by both the die and a mandrel. In another embodiment the die is a deformable die and the cavity tapers so that the die is caused to close over and shape the workpiece during drawing.

METHOD AND APPARATUS FOR SHAPING TUBES

BACKGROUND

This invention relates to improvements in shaping elongated workpieces and relates in particular to a new and novel method and apparatus for shaping tubes.

In drawing and sinking elongated workpieces such as bars and tubes considerable difficulty is experienced in maintaining accurate alignment of the draw bench, of the mandrel (where used), and of the die itself. Vibrations ordinarily encountered in manufacturing facilities frequently cause misalignment. Also, the operation of the drawbench itself may cause such misalignments. Wear of drawbench parts may also throw the bench out of alignment.

Additionally, in my U.S. Pat. No. 3,327,513 I disclose a method for tapering tubes wherein tubes are drawn into conformity with a tapered mandrel by forcing an expandable die or drawing ring over the tube with the mandrel inserted therein. Although this procedure is successfully employed to produce tapered tubular objects, it does not readily lend itself to mass production techniques. After each tube is drawn it must be individually stripped from the mandrel and a new mandrel-tube assembly and die mounted to the die holder and retaining plate and aligned for the next drawing operation. Such time consuming procedures detract from the attractiveness of the process particularly where it is desired to turn out quantities of parts.

I have now devised a method and apparatus that make it possible to reproduce drawn tubes with accuracy and precision not heretofore possible. Further, I find that my invention is particularly adaptable to drawing tapered tubes by the expandable die technique.

My method and apparatus lends itself to modern rapid production procedures whether one is sinking, drawing, or tapering workpieces.

In one embodiment of my invention a workpiece is axially formed in a chamber that is provided with a piston-shaped die or die holder.

The piston and chamber type of construction is particularly amenable to accurate alignment. Consequently, by providing an axially aligned die opening in the piston and by axially positioning a workpiece in the chamber, it is possible to draw or sink the workpiece by driving the piston axially within the chamber over the workpiece to form the workpiece with a degree of precision and reproducibility not heretofore known. Where tube drawing, of course, a mandrel must first be axially positioned within the chamber.

In another embodiment of the present invention, the inner chamber or the chamber cavity walls vary tangentially from the axis of the chamber. In this embodiment the piston or die is constructed of a deformable material such as copper, brass, or an elastomeric material. The workpiece is axially positioned in the chamber and the deformable die is forced through the chamber over the workpiece. The cavity wall causes it to close over and form the workpiece in accordance with the tangentially varying cavity wall.

A particularly useful application of this embodiment of my invention relates to tapering. For example, a tapered mandrel may be axially mounted within a chamber formed with inner walls that at least substantially conform in shape to the mandrel so that the spacing between the mandrel and the walls of the chamber are substantially uniform. The tube is positioned over the mandrel within the chamber and a deformable die is forced through the chamber from the large end of the mandrel to the small end. The wall of the chamber forces the die against the workpiece and causes it to conform with the mandrel surface thus forming a tapered tube.

This arrangement automatically effects a degree of alignment difficult to attain by my prior procedures and, as will be obvious from the drawings and accompanying detailed description, lends itself well to automatic processing procedures.

The invention is best described in conjunction with the drawings wherein:

FIG. 1 is an elevational view in cross-section showing a chamber with a mandrel, die, and workpiece mounted therein and constructed in accordance with the present invention;

FIG. 2 shows the apparatus of FIG. 1 during drawing;

FIG. 3 is a cross-sectional view of a chamber with a mandrel, tube, and die mounted therein in conformity with the practice of the present invention when tapering tubes;

FIG. 4 is the view of FIG. 3 after drawing;

FIG. 5 is a fragmented cross-sectional view of the apparatus of FIGS. 3 and 4 showing a tube being stripped from the mandrel;

FIG. 6 is a cross-sectional view of a chamber that constitutes another embodiment of the present invention shown in an open position and showing the ends of mandrels positioned for automatic insertion into the chamber;

FIG. 7 is a fragmentary perspective view of segment 34 of FIG. 6;

FIG. 8 is a cross-sectional view of the chamber of FIG. 6 shown in its closed position and containing the tube and die positioned therein and with the mandrels positioned for tapering;

FIGS. 9 and 10 are cross-sectional views of the apparatus of FIG. 6 showing the die and tube in different stages of forming; and

FIG. 11 is a fragmentary cross-sectional view of the end of the apparatus of FIG. 8 showing the tube being stripped from the mandrel.

In FIG. 1 there is shown a cross-sectional view of a cylindrical chamber 11 that is similar in construction to a hydraulic cylinder that has been divided into two parts horizontally (segments 11a and 11b) and clamped or bolted together as shown at 13. Positioned within cylinder 11 is a piston 15 (also shown in cross-section) which may be identical to that used in hydraulic cylinders in that it is provided with sealing rings 17. Chamber 11 is also provided with a hydraulic fluid source 19 and a pressure relief outlet 21 which permits one to drive the piston in the direction of the arrow with hydraulic force.

Piston 15 is also provided with an opening 23 and axially positioned seat 23a designed to receive a drawing die 25.

There is positioned at either end of chamber 11 axially aligned clamps 27 that are disposed to receive a mandrel 29.

Mandrel 29 is provided with an extending stem 29a which provides a tube restraining shoulder 29b.

Operation of the device of FIG. 1 consists of removing segment 11a, positioning the mandrel through the die seat with die 31 and pointed workpiece 33 positioned thereon, abutting the die seat of piston 15 with the die, closing and sealing segment 11a, and providing hydraulic or fluid pressure behind piston 15 through conduit or source 19 so that the cylinder is forced through the chamber and workpiece 33 is drawn over mandrel 29 (see FIG. 2).

With this arrangement, precision drawing can be effected on each stroke.

The various possible modifications of the device of FIG. 1 will be obvious to those skilled in the art of metal working. Fluids other than hydraulic (i.e., gas, particulate materials, etc.) can be used. The die and piston can be integral. Many chamber opening devices can be employed. Piston 15 can be driven by mechanical forces. When sinking mandrel 29 is omitted and workpiece 33 is axially anchored to clamps 27 (in this event, the workpiece must, of course, be of greater length). The workpiece may be solid metal (bars, rods, etc.).

The embodiment of FIGS. 3 to 5 consists of a cylindrical chamber 10 formed with a tapering inner surface or cavity 12. Deformable die or ring 14 is positioned over the end of the tube 16 that is to be tapered. The die and tube assembly is then positioned within the chamber 10 in the manner shown, with the die 14 fitting snugly in the enlarged end of tapered inner surface or cavity 12.

Tapered mandrel 18 is mounted axially on the plunger 20 of a hydraulic cylinder (not shown) that is positioned axially in relation to chamber 10. When plunger 20 is retracted, the mandrel 18 is completely withdrawn from the chamber. When the die 14 and tube 16 are positioned within the chamber 10,

the plunger 20 is extended to position mandrel 18, tube 16, and die 14 within chamber 10 in the manner shown by FIG. 3.

The tapered mandrel and cavity are of substantially complementary shape so that the distance between the mandrel surface and surface 12 is substantially uniform.

Positioned around plunger 20 is a hollow plunger 22 which may be driven by a conventional dual ram and yoke arrangement (not shown) or any mechanical driving means. Hollow plunger 22 extends around the end of tube 16 and bears on the die or ring 14. By exerting sufficient pressure on the back of die 14, the die is forced through the cavity 12 (see FIG. 4). Since the cavity tapers, the O.D. of the die or ring must shrink as the die passes through the cavity and accordingly inward pressure from the surface 12 forces tube 16 to draw onto the surface of the mandrel and forces the die to elongate (see FIG. 4).

Hollow plunger 22 may then be withdrawn and a stripper ring 24 positioned in the end thereof. Plunger 20 is then withdrawn to strip the tube from the mandrel (see FIG. 5). The assembly is now prepared for reloading with a die and tube assembly.

In the apparatus of FIGS. 6-11 chamber 30 is formed from two horizontally disposed segments 32 and 34. Segment 32 is provided with means for raising and lowering the segment into meshing engagement with segment 34 that consists of a vertically disposed plunger 36 that leads to an appropriately mounted hydraulic cylinder (not shown).

Each segment 32 and 34 is formed with one-half of a venturi-shaped cavity 38 which is completed when the segments are in meshing engagement.

Venturi-shaped cavity 38 is not of true venturi configuration in that one side of the venturi 38a tapers from a slightly larger diameter than the other side 38b. The end of each side of venturi cavity 38 terminates in a nontapering chamber 40a and 40b. Cavity 38 and chambers 40a and 40b are provided with end openings 42a and 42b which are disposed to engage and clamp around the mandrel and tube surfaces in a manner described in greater detail herebelow.

Openings 42a and 42b are provided with seals 47 to form gas-tight seals around the tube and mandrel. Also, seals are provided between segments 32 and 34 (see FIG. 7).

Segment 32 is provided with openings 43a and 43b leading to chambers 40a and 40b. Openings 43a and 43b lead to conduits 45a and 45b which in turn communicate with a gas pressure source and a vacuum source respectively (not shown). Opening 43a is positioned rearwardly in chamber 40a (toward gripper 44a) to leave space for die 64 to be positioned forwardly in respect to this opening (toward surface 38a).

Tube and mandrel grippers 44a and 44b which are shown to be vertically positionable by plungers 46 that lead to appropriately positioned hydraulic cylinders (not shown) are stationed adjacent either end of openings 42a and 42b. Grippers 44a and 44b are preferably keyed to their adjacent segments 32 and 34 for accurate positioning (see FIG. 7).

Spring loaded tube stripping bolts 48 are attached to, positioned around, and extend slightly beyond the tube and/or mandrel gripping face of grippers 44a and 44b (see FIG. 7).

Tapered mandrels 50 and 52 mounted to plungers 54 and 56 which lead to appropriate hydraulic cylinders (not shown) are axially positioned in respect to chamber 38. Mandrel 52 is provided with a locking pin 58 that is disposed to engage a receptacle 60 formed in the end of mandrel 50 when both plungers are extended to form a venturi-shaped mandrel within chamber 38. Since the taper of surface 38a is greater than the taper of surface 38b, the spacing between mandrel 50 and surface 38a will be greater than the spacing between mandrel 52 and surface 38b. Preferably the spacing between the mandrels and surfaces 38 will be uniform (though differing between 38a and 38b).

In operation, segment 36 is raised and grippers 44a and 44b are opened (see FIG. 6). A tubular workpiece 62 of appropriate length having an expandable die 64 positioned thereon is seated in segment 34 so that one end is within the

jaws of grippers 44a but does not extend beyond the spring-loaded bolts 48 (see dotted outline FIG. 6).

The plungers 54 and 56 are then extended, positioning mandrels 50 and 52 within tubular workpiece 62.

5 Plunger 36 is actuated to bring segment 32 into engagement with segment 34 and sealing the cavity 38 around workpiece 62 and mandrel 50 and mandrel 52, respectively. Plungers 46 are actuated to cause grippers 44a and 44b to engage tube 62 and mandrel 50 and mandrel 52 respectively (see FIG. 8).

10 The apparatus is now prepared for forming and die 64 is caused to move over mandrel 50 and tube 62 by a sudden supply of gaseous pressure within chamber 44a behind the die supplied through the conduit 45a and passageway 43a. Optionally the die may be propelled by a vacuum created in chamber 40b by being drawn through conduit 45b and opening 43b. Preferably, the force driving die 64 will be a combination of such driving forces.

15 As die 64 progresses over tube 62 and mandrel 50, the die is compressed and deformed by the diminishing area of the space between surfaces 38a and mandrel 50. Thus tube 62 is formed over mandrel 50 (see FIG. 9). Once the die reaches mandrel 52 it commences to expand drawing workpiece 62 onto the surface of mandrel 52 (see FIG. 10). Although die 62 is now expanding, it will not reassume its original shape due to the fact it has elongated while on mandrel 50. However, since the distance between mandrel 52 and surface 39b is less than the distance between mandrel 50 and surface 38a, the die will continue to seal cavity 38 and the gaseous propelling force will not escape around the die.

20 25 30 35 When the die reaches chamber 40b and workpiece 62 is formed, plunger 36 is retracted slightly to relieve the seal and pressures within cavity 38 that may interfere with the removal of the mandrels and/or workpiece. Plungers 46 are retracted a predetermined amount so that grippers 44a and 44b release the mandrels and workpiece, but are positioned so that spring-loaded bolts 48 will engage the edge of workpiece 62. Plungers 54 and 56 are then retracted. Spring-loaded bolts 48 engage the leading edge of workpiece 62 and strip it from the mandrels (see FIG. 11). Die 64 is, of course, also stripped from the mandrel 52 by chamber 40b or grippers 44b. The plunger 36 is then further retracted, formed workpiece 62, and used die 64 are removed and the assembly is prepared for another workpiece and die.

40 45 50 It will be appreciated that where the deformable die 64 of the apparatus of FIGS. 6-11 is constructed of a nonelastomeric material such as red brass, sinking is only partially possible. Sinking is possible only in that portion of the cavity 38 represented by the surfaces 38a since mandrel 52 is essential to cause the die to expand and form the workpiece.

55 It will be obvious to those skilled in the art that the apparatus of FIGS. 6-11 is readily adaptable to tapering tubes rather than forming a venturi shape. The die may be propelled through the cavity by any force mechanical or chemical. For example, explosives may be advantageously used to drive the die. Also, cavity 38 may be readily adapted for the use of mechanical die driving means such as the hollow plunger 22 of the device of FIGS. 3-5.

60 65 Die 64 will normally be constructed of a deformable metal such as red brass, however, many materials may be employed as die materials. For example, where the tube 62 is constructed of thin wall metal, it may be desirable to employ a die constructed of an elastomeric resin. In this instance it may be desirable to provide identical spacing between wall 38b and mandrel 50 since the elastomer will recover from elongation when passing over mandrel 52.

70 75 In the embodiments of the present invention shown and described above where tubular shapes are drawn over a mandrel, the cross-sectional dimensions of the workpiece may be reduced, the tubes may be elongated, tapered and/or formed into venturi configurations. It will also be appreciated that as in conventional drawing over a mandrel and through a die wall sizing may be effected either in conjunction with one or more of the aforementioned forming procedures or as an independent forming step.

For example, the walls of workpiece 33 of the embodiment of FIG. 1 may be merely reduced in gage rather than the workpiece being reduced in diameter or the wall gage may be reduced simultaneously with reducing the diameter of the tube. Obviously where the wall gage is reduced the tube is caused to elongate.

The mandrel 18 of the embodiment of FIGS. 3 and 4 may have a slightly greater or slightly less taper than the cavity surfaces 12 so that the workpiece 20 is formed into a tapered tube having an increasing or decreasing gage from its large diameter to its small diameter. In a like manner, the spacing between mandrels 50 and 52 and cavity surfaces 38a and 38b may be selected to effect a desired gage or gage variation in a resultant venturi shape (FIGS. 8-10).

The ability to size walls and particularly to vary the gage of tapered tubes by varying the taper of the mandrel and cavity is significant for the production of tapered golf club shafts, light poles, etc., where the parameters of mechanical strength distribution along the tube dictate the use of heavier gage metal for greater relative strength in the small diameter end of the tube.

For the purposes of the present invention, the term "venturi shape" shall be interpreted to apply to the shape of a surface whether the outside surface of a solid member or the inside surface of a chamber and shall mean roughly the shape of opposing cones aligned approximately apex to apex which may or may not have a straight or parallel surfaced area separating them.

For the purposes of the present invention the term "tube" shall include any hollow elongated body such as pipe, conduit, etc. The term shall also include cross-sectional shapes that are not necessarily round but which may be oblong, square, triangular, hexagonal, octagonal, etc. The mandrel, of course, must conform in shape to the tube or elongated member being drawn.

I claim:

1. Apparatus for forming an elongated workpiece comprising:

- a. a chamber formed with at least one bearing surface disposed to guide an axially positioned die so that its orifice substantially coincides with the axis of said chamber when the die is axially forced through said chamber;
- b. means for axially mounting said workpiece within said chamber; and
- c. means for forcing a die axially through said chamber while in contact with said bearing surface and over said workpiece so as to form said workpiece;
- d. wherein the inner walls of said chamber form said bearing surface and the distances between them vary along the axis of said chamber, and said die is a deformable die.

2. The apparatus of claim 1 wherein a mandrel is axially positioned within said chamber said mandrel being of substantial complementary shape in respect to said inner walls so that the distance between the mandrel surface and said inner walls is substantially uniform.

3. The apparatus of claim 1 wherein said bearing walls taper from a large diameter to a small diameter.

4. The apparatus of claim 1 wherein said bearing walls are of substantial venturi configuration.

5. The apparatus of claim 1 including an axially positioned mandrel having substantially complementary shape to said walls.

6. The apparatus of claim 4 including an axially positioned mandrel having substantially complementary shape to said walls.

7. The apparatus of claim 2 wherein said mandrel tapers relative to said inner walls so that the distances between the mandrel surface and said inner walls vary along the axis of said

chamber.

8. The method of forming an elongated workpiece comprising:

- a. axially aligning a workpiece in a chamber having at least one bearing surface disposed to guide a die so that its orifice coincides with the axis of said chamber; and
- b. forcing a die axially through said chamber over said workpiece while in contact with said bearing surface so as to form said workpiece;
- c. wherein the inner walls of said chamber form said bearing surface and the distances between them vary along the axis of said chamber, and said die is a deformable die.

9. The method of claim 8 including the step of axially positioning a mandrel within said chamber that has a substantially complementary shape in respect to said inner walls, positioning a tubular workpiece over said mandrel and forming said workpiece by forcing a deformable die through said chamber over said workpiece and mandrel.

10. The method of claim 9 wherein said mandrel and inner walls are tapered so that said tubular workpiece is tapered.

11. The method of claim 9 wherein said mandrel and inner walls are venturi shaped so that said tubular workpiece is formed into a venturi shape.

12. The method of claim 9 wherein said mandrel tapers relative to said inner walls so that the distances between the mandrel surface and said inner walls vary along the axis of said chamber.

13. Apparatus for forming a tubular member comprising:

- a. a housing formed with an elongated cavity and axially aligned openings at either end, the inner walls of said cavity being positioned to guide an axially oriented die through said cavity while maintaining its axial alignment, said housing being divided into two longitudinal sections, each said segment containing an elongated portion of said cavity so that when said segments are aligned in abutting relationship said cavity is formed;
- b. means for separating said segments and bringing said segments into aligned abutting relationship;
- c. means for axially positioning an elongated workpiece in the cavity portion of at least one of said segments so that said workpiece may be so positioned while said segments are separated; and
- d. means for forcing an axially oriented die through said cavity over said workpiece after said workpiece is positioned and said segments are brought into abutting relationship;
- e. wherein means are provided for positioning a mandrel in said cavity so that a tubular elongated workpiece may be positioned in the cavity portion of said segment and said mandrel may be positioned therein and said die may form said tube between said inner cavity wall and said mandrel; and
- f. wherein said cavity is tapered and said mandrel is of substantially complementary shape so that a deformable die will form said tubular workpiece into a tapered tube.

14. The apparatus of claim 13 wherein said cavity is venturi shaped and said mandrel is of substantially complementary shape so that a deformable die will form said tubular workpiece into a venturi shape when forced through said cavity.

15. The apparatus of claim 14 wherein the venturi shape is of slightly greater diameter where the die is forced to taper downwardly than where the die is forced to taper upwardly.

16. The apparatus of claim 15 wherein gripping means are positioned at either end of said cavity to grip the ends of the tubular workpieces and the mandrel and seal the cavity and means are provided for creating greater fluid pressure in back of said die than in front of said die so as to propel said die through the cavity.
